US00D756960S

(12) **United States Design Patent**
Bapu et al.

(10) **Patent No.:** **US D756,960 S**
(45) **Date of Patent:** **** May 24, 2016**

(54) **SPEAKER**

(71) Applicants: **Pavan Bapu**, Chicago, IL (US); **Jeffrey Parrish**, Itasca, IL (US)

(72) Inventors: **Pavan Bapu**, Chicago, IL (US); **Jeffrey Parrish**, Itasca, IL (US)

(73) Assignee: **GRAMOVOX, LLC**, Chicago, IL (US)

(**) Term: **14 Years**

(21) Appl. No.: **29/455,422**

(22) Filed: **May 20, 2013**

(51) **LOC (10) Cl.** **14-03**

(52) **U.S. Cl.**

USPC **D14/208**

(57) **CLAIM**

The ornamental design for a speaker, as shown and described.

DESCRIPTION

FIG. 1 is a perspective view of a speaker showing our new design;

FIG. 2 is a front view thereof;

FIG. 3 is a back view thereof;

FIG. 4 is a right view thereof;

FIG. 5 is a top view thereof; and,

FIG. 6 is a bottom view thereof.

Those portions of the figures that are presented in broken lines merely illustrate the environment of the design and are not part of the claimed design.

1 Claim, 5 Drawing Sheets
